VENDING MACHINE

Joseph G. Llovera, New York, N. Y.

Application May 24, 1937, Serial No. 144,531

1 Claim. (Cl. 232—1)

This invention relates to a machine for vending goods, wares and merchandise, and the machine may be used advantageously for vending various edible products or articles of food and drink upon the insertion of one or more appropriate coins or tokens.

An object of the invention is the provision of a machine of the indicated character which requires the insertion of one or more appropriate coins or tokens to enable a patron to remove the selected product, and which does not require the patron to open a closure member or door, this being accomplished automatically by the mere manipulation of a suitable actuator after the insertion of one or more coins or tokens.

A further object of the invention is to prevent the insertion of a coin or token in the absence of a product or article to be vended.

A further object of the invention is to provide means in a machine of the indicated character, which indicates to an attendant when to load the machine, and enables the attendant to release the coin or coins while resetting the machine after it has been loaded, and prevents a patron from reaching beyond a certain point when the machine is open.

With the foregoing and other objects in view, the invention resides in the embodiment thereof, which by way of example is illustrated in the accompanying drawings in which:

Fig. 1 is a perspective view of a machine embodying the features of the invention.

Fig. 2 is a top view of the machine, portions thereof being broken away.

Fig. 3 is a rear view of the machine, portions thereof being broken away.

Fig. 4 is a section taken on the line 4—4 of Fig. 3, and looking in the direction indicated by the arrows.

Fig. 5 is a section taken on the line 5—5 of Fig. 3, and looking in the direction indicated by the arrows.

Fig. 6 is a section illustrating the manner in which a coin is disposed for actuation, to release the front door, to open the machine and enable removal of the product or article to be vended; and

Fig. 7 is a view of the door latch and illustrating the manner in which it is released.

Referring now more particularly to the drawings, it will be apparent that the machine includes a frame structure 10, which includes a front panel 11, end walls 12 and 13, respectively, a rod 14 supported at the ends by the walls 12 and 13, and extending parallel to the panel 11 in spaced relation thereto, and a rod 15 also supported by the walls 12 and 13 at the rear of the structure 10.

The compartment 16 for the product or article to be vended is formed within the structure 10

in conjunction with the end wall 12. The compartment 16, in addition to the wall 12, includes a top wall 17, end wall 18 and bottom wall 19. A front closure member or door 20 is slidable with respect to the compartment 16 and an opening 21 in the front panel 11. The door 20 has a pane of glass 22 to enable a patron to see the article within the compartment 16. A rear closure member or door 23 is swingable with respect to the compartment 16. The door 20 is suspended for sliding movement from the rod 14 by a hinge 24 on one end and at the top of the door engaged with said rod 14, and by a rod 25 secured to the other corner and at the top of the door 20, said rod resting on the rod 14. The rod 25 extends rearwardly and has a downwardly projecting portion 26 beyond the rod 15, said portion 26 constituting a handle. The door 23 has a hinge connection at the top with the rod 15 as at 27, so that the door 23 may be swung to an open and closed position with respect to the compartment 16. The door 23 swings to its closed position by gravity. One corner of the door 23 is cut away as at 28, and has a handle 25 integral therewith.

When the front door 20 is in its closed position, the handle 26 will be disposed in proximity to the wall 12 and will be in alignment with the cut away 28 so that an attendant may swing the door 23 to an opened position and load the compartment 16, after which the door 23 may be permitted to swing to its closed position. When the front door 20 is in its open position, the handle 26 will be in an obstructing position to prevent the movement of the door 23 to a fully open position. This prevents a patron from reaching beyond the door 23 when the compartment 16 is open.

The front door 20 is moved automatically to its open position, when released, by resilient means in the form of a coiled band spring 30 having one end thereof connected with the lower edge of the door and its other end connected with a holder 31 fixed to the lower rod 14. When the door is returned to its closed position by the attendant manipulating the handle 26, the spring 30 will be rewound and will then have sufficient tension to move the door 20 to its open position when released in a manner to be hereinafter explained. The door 20 slides between the front panel 11 and the rods 14. The lower edge of the door 20 is guided by a guide lug 20' which moves between the lower rod 14 and a rod 14'.

The release of the door is accomplished by means of a coin control device upon the insertion of one or more appropriate coins or tokens and by subsequent manipulation of the device by the patron. This device includes a shaft 35 which is disposed vertically and has up and down 60

movement in a block 36 secured to the rear side of a plate 37 secured to the upper and lower rods 14. The shaft 35 also has turning movement in opposite directions, that is to say, direct turning movement and return, or reverse turning movement. An arm 38 is rigidly connected with the lower end of the shaft 35 below the block 36, and the other end of the arm has rigidly secured thereto a vertically disposed bar 39. A plurality of coin stops 40 are carried by the bar 39. There are four stops 40 in the present instance. These stops 40 are vertically spaced. Each stop 40 is in the form of a screw which is therefore adjustable into and out of a coin supporting position. Thus, provision is made for optionally requiring the use of one or more appropriate coins or tokens in the operation of the device. In the present instance these stops are so arranged that when the three uppermost are adjusted to a known supporting position it will require four nickels to operate the device, these being supported by the lowermost stop 40. It will be obvious that the stops may be adjusted to require three nickels, two nickels, or one nickel. When one nickel is required to operate the device, the uppermost stop 40 will be adjusted to a supporting position as illustrated in the present instance. A coin chute 41 projects inwardly and downwardly and then laterally with respect to the panel 12, the upper end of the chute 41 communicating with a coin slot 42, in the panel 11, said slot being surrounded by a plate 43 secured to the outside of the panel 11. The chute 41 is disposed in front of the bar 39, and has a slot 44 therein into which the stops 40 project when the bar 39 is in its normal position. Resilient means in the form of a contractile spring 45 serves to cause the upward axial movement of the shaft 35 and also the return turning movement of the shaft. This spring 45 has one end thereof secured to the block 36, as at 46, and its other end is secured to a hook 47 carried by the arm 38. The return turning movement of the shaft 35 is limited by reason of the arm 38 engaging the chute 41, and this brings the bar 39 into its normal position to dispose the stops 40 in operative relation to the coin chute 41. A rock lever 48 is supported by the block 36, and said lever has a pressure member 49 on one end and an arm 50 on its other end. A link 51 has one end thereof pivotally connected as at 52 with the arm 50, and the other end of the link is pivotally connected as at 53 with the inner end of an actuator 54. This actuator is mounted for axial movement in opposite directions in a guide 55 secured to the plate 37 above the upper rod 14. The actuator 54 is under the influence of resilient means in the form of a contractile spring 56, which has one end thereof secured to the pivot 53 and its opposite end is connected with the plate 37 as at 57. The spring 56 serves to retract the actuator 54 and also to cause return movement of the lever 48 thru the intervention of the link 51. The return movement of the actuator 54 by the spring 56 is limited by a stop member 58 carried by the actuator and engageable with the plate 37. The return movement of the rocker is therefore limited by the member 58, and also by a notched collar 59 secured to the lever 48 and the walls of said notch being engageable with a stop 60 carried by the block 36. A spring actuat-

ed pivoted latch member 61 carried by the plate 37 is engageable with the hanger 24 to retain the front door 20 in its closed position. An actuator 62 on the upper end of the shaft 35 operates the latch member 61 when the shaft 35 is moved downwardly, thereby releasing the latch member and permitting the door 20 to be moved to its open position by the spring 30.

The down axial movement of the shaft 35 is accomplished when a coin is inserted in the chute 41. The coin moves downwardly in contact with the uppermost stop 40. The patron may then push the actuator 54 inwardly, which will cause the member 49 to exert pressure on the coin, thru the intervention of the lever 48 and link 51. As the door 20 moves to its open position, the rod 25 encounters an L-shaped arm 63 projecting from the actuator 62. This causes the direct turning movement of the shaft 35, and as a consequence the bar 39 will be moved out of its normal position allowing the coin to drop and be conveyed by the chute 41 into any suitable receptacle. When the attendant returns the door 20 to its closed position by manipulating the handle 26, the latch member 61 will re-engage the hanger 24 and releasably retain said door 20 in its closed position. At the same time the bar 39 and stops 40 carried thereby will be brought to a normal relation to the chute 41 by the spring 45.

The front panel 11 has a sight opening 64 in alignment with the coin chute so that the coin or coins may be visible to the patron. The said panel also has an index 65 to designate the price and character of the article within the compartment 16. An electric lamp and reflector 66 project rays of light thru an opening 67 in the end wall 18 into the compartment 16 to illuminate the latter so that the article or product to be vended will be visible at all times.

The rod 25 carries an obstructing member 68 which is disposed transversely of the coin chute 41 when the door 20 is in its open position in order to prevent the insertion of a coin in the chute 41 in the absence of an article or product in the compartment 16.

It is to be understood that this improvement is capable of extended application and is not confined to the exact showing of the drawings nor to the precise construction described and, therefore, such changes and modifications may be made therein as do not affect the spirit of the invention nor exceed the scope thereof as expressed in the appended claim.

What is claimed as new and useful is:

A vending device comprising a boxlike casing; a rear service door vertically swingably mounted on said casing; a horizontally sliding door closing the front of the casing; spring urging means associating the front door and the casing tending to move said door into opened position; a latch for holding said front door in closed position; and means comprising an arm, mounted on the front door and slidably therewith, for overlying parts of and preventing opening of the rear service door except when the front door is closed, and a projecting formation on the arm engaging with parts of the latch for preventing opening of the front door except when the rear door is closed.
